US0D1009256S

(12) **United States Design Patent** (10) Patent No.: **US D1,009,256 S**
(45) Date of Patent: ** *Dec. 26, 2023

(54) **ABSORBENT CORE**

(71) Applicant: **Medline Industries, Inc.**, Mundelein, IL (US)

(72) Inventors: **John Fitter**, Greenwood, SC (US); **Daniel B. Love**, Libertyville, IL (US)

(73) Assignee: **Medline Industries, LP**, Northfield, IL (US)

(*) Notice: This patent is subject to a terminal disclaimer.

(**) Term: **15 Years**

(21) Appl. No.: **29/726,335**

(22) Filed: **Mar. 2, 2020**
